UNITED STATES PATENT OFFICE.

ELBERT F. TURNER, OF SPRINGFIELD, MISSOURI.

MEDICINE-CABINET.

1,368,863.

Specification of Letters Patent. Patented Feb. 15, 1921.

Application filed January 3, 1919. Serial No. 269,443.

To all whom it may concern:

Be it known that I, ELBERT F. TURNER, a citizen of the United States, residing at Springfield, in the county of Greene and 5 State of Missouri, have invented new and useful Improvements in Medicine-Cabinets, of which the following is a specification.

The object of the invention is to provide means, particularly adapted for use in drug 10 stores, dispensaries, private residences, etc., for containing medicines including those which are recognized as poisonous, under such conditions as to maintain a distinct separation of the medicines or remedies 15 which are relatively poisonous and non-poisonous in separate compartments of the cabinet and to provide for giving access to one of the classes of medicines in one compartment only when the other is rendered 20 inaccessible as by being locked in another separate compartment, as, for instance, when a latch is turned to open the door of one compartment the door of the other compartment becomes securely locked with the 25 same operation; and also to provide means in this connection whereby a signal, either audible or visual or both, is maintained with reference to the open compartment of the cabinet as long as the contents thereof are 30 accessible.

To this end the invention consists in the construction, combination and relation of parts hereinafter described in connection with a preferred embodiment, it being understood however that changes in form, proportion and detail may be resorted to without departing from the spirit of the invention.

In the drawings,

40 Figure 1 is a view of a cabinet constructed in accordance with the invention, one of the compartments of the same being shown opened.

Fig. 2 is a perspective view of the locking 45 mechanism which is employed mutually in reference to the doors of both compartments of the cabinet.

Fig. 3 is a vertical sectional view of the same on the plane indicated by the line 3—3 50 of Fig. 2.

Fig. 4 is a horizontal section on the plane indicated by the line 4—4 of Fig. 3.

Fig. 5 is a detail view of one of the bolt carrying levers.

55 Fig. 6 is a diagrammatic view, partly in

section, of one of the electric circuits and the cut-out switch.

In the construction illustrated the cabinet is provided with two independent compartments which are designated respectively 60 as 10 and 11 and may be known respectively as general and poison compartments in that the former is adapted to contain those general medicines and remedies which are not ordinarily classified as poisonous, while the 65 latter is designed to contain those medicines which are so classified and are regarded as dangerous in the hands of irresponsible or ignorant parties and which ordinarily are only sold on prescription; and to the end 70 that the druggist or drug clerk or other person may be surrounded by every possible safe-guard in the handling of these products, so as to avoid mistakes in filling prescriptions and the like, said compartments 75 are provided with independent closures 12 and 13 consisting for example of doors which being hinged at their outer edges are adapted to fold toward each other as to bring their free edges into relation with a common 80 locking mechanism indicated at 14. The purpose is to provide a locking mechanism which will permit of the opening of either door, to give access to the corresponding compartment of the cabinet only when the 85 other door is closed and locked, and incidentally thereto to provide distinctive means whereby the poison may be identified and distinguished from the general compartment, or the part of the cabinet containing 90 the general remedies, as for example by arranging in the former in a prominent position a visual signal bearing for example the word "Poison." This may be constructed in the form of a transparent or translucent 95 plate 15 bearing in clear distinguishable characters the sign word, and locating in rear thereof an electric lamp or similar illuminating device as shown at 16, and at the same time an audible signal is provided 100 for and is designed to be located in or near the compartment which contains medicines recognized as poisonous, said signal consisting for example of a bell 17. It is preferable to employ electrically operated signaling devices of both the visual and audible types in the compartment 11 and to arrange them in circuits for example with a battery 19 or other source of energy controlled by 105 switches located for example in the lock 110

mechanism and therefore actuatable in opening and closing by the manipulation of the lock mechanism in connection with locking or unlocking the respective doors of the 5 compartments. In the compartment 10 may be arranged an electric lamp 16' arranged in circuit with a battery 19'.

The means illustrated for accomplishing this purpose embody what may be design- 10 nated as locking bolts 20 and 21 arranged in the casing 14 and disposed oppositely for engagement respectively with the doors 12 and 13, said bolts being provided with pivotal carriers 22 and 23 consisting of inter- 15 mediately mounted levers whose free ends carry wards 24 arranged in the paths of latches 25 which are mounted respectively upon the cabinet compartment doors so that when the latch of one door is turned from 20 its engagement with the lock casing to release its door, the turning movement being accomplished by an exposed knob or grip 26, the related pivotal carrier of the locking bolt for the other cabinet door is released 25 and is free to be actuated by a spring 27 located in the casing and so disposed as to project said locking bolt into engagement with the other compartment door. For example when the latch of the poison com- 30 partment door 13 is turned to open the latter, the locking bolt 20 is projected to engage and secure the door 12 against opening and this engagement is maintained until the door 13 is closed and its latch turned to a 35 locking position with the actuating spring under restraint in order that the turning of the latch carried by the door 12 and which is accompanied by the projection of the bolt 21 to lock the door 13 serves to release the door 12. The engagement of the door 12, or 40 either door, in other words, by the related locking bolt, is accomplished automatically by the turning of the latch of the other door, and that locking engagement is retained 45 until the second named door has been closed and its latch turned to secure it in such position.

In order that the signaling devices may be actuated with relation respectively to the 50 compartments as they are opened the elements of each switch or circuit closer are carried respectively by the lock casing as shown at 28 and the corresponding bolt carrier as shown at 29, the circuit wires 30 being connected respectively therewith, and the relation between said elements being such that for example when the locking bolt 20 is released for engagement with the door 12 by the opening movement of the latch on 55 the door 13, the circuit of the signal or signals in the compartment 11 is closed and this condition maintains until the door of the open compartment has been closed and locked by the turning of the latch carried 60 thereby.

The maintenance of the signal in its active condition, whether it be visual or audible or both, serves as an everready reminder of the character of medicine or drug contained in the compartment which has just 70 been opened or made accessible thereto, and under any circumstances the desired access to either compartment is prevented until the door of the other compartment has been returned to its closed position and its latch 75 engaged with the lock casing in order that the door of the said other compartment may be released from the restraining effect of the locking bolt related therewith.

Having thus fully described my invention, I claim:

1. A cabinet having a pair of independent closures, locking mechanism, one for each closure, and an interrelated controlling means between said locking mechanisms 85 and governing said locking mechanisms so as to throw the locking mechanism of one closure into action to lock said closure on the release of the other locking mechanism and opening movement of the other closure. 90

2. A cabinet having a pair of independently movable doors, a pair of locking devices, one for each door, and an associated alternating-interlock-controlling means governing said locking devices for automatically locking either door when the other door is unlocked and open. 95

3. A cabinet having a pair of separate compartments, doors for closing the respective compartments, and a locking mechanism inactive when both doors are closed so as to permit either door to be opened, said locking mechanism being operative to lock either closure when the other closure is opened. 100

4. A plural compartment receptacle having independent compartment closures and locking mechanism embodying sets of locking devices, one actuatable to lock one closure when the other is actuated to release another closure, and vice versa. 110

5. A plural compartment receptacle having independent compartment closures and locking mechanism common to said closures and provided with a locking bolt and a latch for each closure, and means whereby the engaging and disengaging movements of the latch of one closure cause reverse movements of the locking bolt of another closure. 115

6. A plural compartment receptacle having independent compartment closures and locking mechanism common to said closures and provided with a spring actuated locking bolt and a mutually operable latch for each closure, and bolt retracting means for each closure disposed in the path of locking movement of the latch of another closure. 120

7. A plural compartment receptacle having independent compartment closures and locking mechanism common to said clo- 130

sures and provided with independent spring actuated locking bolts, carriers for the bolts and a door holding latch for each closure, the carrier for the bolt of one closure being 5 arranged in the path of locking movement of the latch of another closure for actuation to disengage the bolt of the first named closure.

8. A receptacle having a plurality of independently movable closures, independent locking elements related with the respective closures, and means for reversely actuating the elements, whereby one moves to engaging position when another is moved to releasing position.

9. A cabinet having a pair of independently movable doors, a locking mechanism, including a locking bolt and a controlling knob, associated with each door, for locking 20 the same in closed position, and means operative when the knob of either door is actuated and said door opened to control the locking bolt of the other door to lock said other door in closed position.

25 10. A cabinet having a pair of doors, a

locking mechanism for each door, and a connecting means whereby when either door is locked by its locking mechanism the locking mechanism of the other door is released.

11. A receptacle having a pair of separate and independent closures, and a locking mechanism inactive when both closures are closed so as to permit either closure to be opened, said locking mechanism being operative to lock either closure when the other closure is opened.

12. A cabinet having a pair of independent closures, a locking mechanism for each closure, each locking mechanism including 40 a manually operable actuating element, and an interrelated controlling means for said locking mechanisms, governing the same for rendering either locking mechanism operative to lock a closure when the actuating element of the other locking mechanism is operated to render said other locking mechanism inoperative to effect the release of another closure.

In testimony whereof I affix my signature. 50
ELBERT F. TURNER.
